BRAKE SHOE

Filed Feb. 21, 1927

FIG. 1

FIG. 3

FIG. 2

INVENTOR
GEORGE J. THOMAS
BY
Dr. W. McConkey
ATTORNEY

UNITED STATES PATENT OFFICE.

GEORGE JOSEPH THOMAS, OF SOUTH BEND, INDIANA, ASSIGNOR TO BENDIX BRAKE COMPANY, OF CHICAGO, ILLINOIS, A CORPORATION OF ILLINOIS.

BRAKE SHOE.

Application filed February 21, 1927. Serial No. 169,873.

This invention relates to brake shoes, and is illustrated as embodied in a shoe for an internal expanding automobile brake. An object of the invention is to provide simplified and positive means for laterally positioning the free end of the shoe, by forming it with spaced flanges or other parts engaging opposite sides of a cam or equivalent brake-applying device.

10 Preferably a thrust roller or the like is mounted in the recess thus formed in the end of the shoe, for operative engagement with the cam, the flanges projecting past the roller on opposite sides to embrace the cam between them.

Other objects and features of the invention, including various novel combinations of parts and desirable details of construction, will be apparent from the following 20 description of one illustrative embodiment shown in the accompanying drawing, in which:

Figure 1 is a vertical section through the brake, just inside the head of the brake drum, and showing the brake shoes in side elevation;

Figure 2 is a partial section on the line 2—2 of Figure 1, showing the novel roller mounting; and

30 Figure 3 is a section through one of the shoes, on the line 3—3 of Figure 1.

The illustrated brake includes a rotatable drum 10, at the open side of which is arranged a suitable support such as a backing plate 12, and within which are arranged three brake shoes, viz: an auxiliary shoe 14 anchored on a pivot 16 carried by the backing plate, a secondary shoe 18 anchored on a pivot 20 carried by the backing plate, and 40 a primary shoe 22 connected to shoe 18 by a floating pivot 24.

Shoes 14 and 22 are shown forked at their lower ends to straddle opposite ends of shoe 18, and are forced apart against the resistance of a return spring 26, to apply the brake, by means such as a cam 28 on a shaft 30 journalled in a bracket 32 secured to backing plate 12, whereupon shoe 22 forces shoe 18 against the drum against the resistance 50 of an auxiliary spring 34.

Each shoe, as best shown in Figure 3, may

be built up of two angle-section steel stampings having cylindrical flanges 36 jointly forming a friction face to which the lining 38 is secured, and flanges 40 jointly forming 55 the stiffening web of the shoe.

Except as further described below, the brake may be of any desired construction, the one illustrated in the drawing and described above being substantially as fully described in Patent No. 1,567,716, granted Bendix Brake Company on December 29, 1925, on application of A. Y. Dodge.

According to an important feature of the present invention, flanges 40 of each of the 65 shoes 14 and 22 are spread apart at the upper end of the shoe to form a recess, in which is arranged a thrust member such as a roller 42 operatively engaging the cam 28, and shown as pivotally mounted on a pin 44 70 pressed into tubular sleeves 46 drawn in opposite directions from flanges 40. It will be seen, however, that flanges 40 project beyond roller 42 on opposite sides, to embrace cam 28 between them and position the shoe laterally. Pin 44 is shouldered at its ends, to space flanges 40 rigidly apart so that they 75 will not bind against the roller 42.

While one illustrative embodiment has been described in detail, it is not my intention to limit the scope of the invention to that particular embodiment, or otherwise than by the terms of the appended claims.

I claim:

1. A brake shoe comprising two parts having portions spaced apart at one end of the shoe, and a thrust member mounted between said portions, said portions projecting beyond said member on opposite sides. 85

2. A brake shoe having two flanges secured together and jointly forming a stiffening web, and spread apart at one end of the shoe to form a recess, in combination with a thrust roller in the recess pivotally mounted on said flanges, said flanges projecting beyond the roller on opposite sides at the extreme end of the shoe. 90

3. A brake shoe having two flanges secured together and jointly forming a stiffening web, and spread apart at one end of the shoe to form a recess, in combination with a thrust member in the recess, said flanges pro- 100

jecting beyond said member on opposite sides at the extreme end of the shoe.

4. A brake shoe having at one end a pair of spaced flanges, a pin extending between the flanges and shouldered at its ends to space them rigidly apart, and a roller on the pin between the flanges.

5. A brake shoe built up of a pair of stampings secured together and spread apart

at one end to form a pair of spaced flanges, 10 a pin extending between the flanges and shouldered at its ends to space them rigidly apart, and a roller on the pin between the flanges.

In testimony whereof, I have hereunto signed my name.

GEORGE JOSEPH THOMAS.
